UNITED STATES PATENT OFFICE

EUGENE ANDERSON, OF NEW YORK, N. Y., ASSIGNOR OF PART INTEREST TO HIMSELF,
H. WALTER GILBERT, SAMUEL C. DRETSIN, AND SAMUEL C. DRETSIN, AGENT

HEAD OR HAT SUPPORTED UMBRELLA

Application filed June 22, 1928, Serial No. 287,631. Renewed December 16, 1929.

As everyone knows there is a great need for what may be called an emergency umbrella, because as everyone knows from disagreeable experience, sudden showers and rains find one without the ordinary umbrella and with no means of obtaining an umbrella except by purchase. The expedient has been tried of meeting this situation by hiring or renting umbrellas, but this may be costly or inconvenient because it involves the return of the umbrella with the alternative of forfeiting the deposit required at the time of hiring. The primary object of my invention is to provide a shield or protector not only for the head gear, but for the person and clothes which will be entirely efficient for the purpose of protection, but above all (and this is a vital commercial requirement) capable of manufacture and sale at a very low cost,— as low, indeed, as ten cents. These shields or protectors to serve the emergency purpose must be available in stores, places of amusement, including theaters, base ball fields and the like, and this means that for carrying in stock or handling at the places of sale, the article must occupy the minimum of space and be so compact as to permit ready or easy handling by the salesman, and yet this must be done without sacrificing or diminishing the ample area required for protecting the clothes and person when the article is in use. In producing the embodiment of my invention about to be described and which is shown in the drawing, I have taken all of these considerations, some of which are conflicting, into account, and have produced an article which meets all of the requirements stated, as well as having other advantages which will be understood from a consideration of such embodiment of my invention.

In the drawings:

Fig. 1 is a perspective view of a shield or protector embodying my invention;

Fig. 2 is a similar view showing the article in the folded or flat collapsed state;

Fig. 3 is a plan view of the paper sheet or blank in which form the article exists in its initial state and before it is completed.

For the sake of lightness and cheapness, I use paper which is fairly heavy, but which

inherently or in itself because of the size of the article must be for protective purposes, cannot stand up under the effect of rain, and therefore, requires to be braced to prevent collapse when in use. The employment of reinforcing or stiffening devices as things separate from the article is objectionable for a variety of reasons. The principal objection is that of cost in manufacture. Another serious objection is that to be given an efficient form, the bracing or reinforcing precludes folding or collapsing of the article when not in use, and, therefore, makes the article objectionable for storage. Nobody would have an ordinary umbrella if it should be in a permanently opened condition. I have discovered that by giving to the sheet or blank a contour from which the sheet can be formed into a pyramidal shape and providing scores or creases radiating in straight lines from the center out to the margin, the article when given its pyramidal form or shape as in use will possess all the stiffness or rigidity required to serve its purpose as a shield or protector even against heavy downpours of rain and yet paradoxically as it may seem, the element of strength thereby provided constitutes the means by which the article when not in use may be collapsed or folded into a flat state. To enable such folding or collapsing, the radial scores or creases should be even in number, and equidistant apart so that they extend diametrically across the article as this provides an even number of similar triangular sides or surfaces which when the article is folded lie flat, one upon the other and thus in its folded state, the article is flat and of triangular form, and requires no more space than that represented by one of the triangular sides.

The paper is preferably treated to render it water-resistant or water-proof, although when used as a mere sun-shade, water-resistant properties are not necessary.

Referring to Fig. 1, it will be seen that the completed or finished article when in use is of pyramidal form, being composed of an even number of triangular sides, 10, with a straight corner, 11, extending from the apex of the pyramid to the base. Such straight

edges are produced by the radial scores or creases, 100, indicated in the blank shown in Fig. 3. The blank shown in Fig. 3 is pentagonal with a cut or incision reaching from the center to the perimeter and with all but a narrow portion of the segment at one side thereof towards the adjacent score or crease, 100 cut away to provide a triangular notch, this being necessary to enable the blank to be formed into the pyramidal shape made up of four triangular sides, and to provide in the strip, 12, extending from the adjacent score or crease an overlap of the adjacent triangular side to unite the blank and avoid a cut or incision through which water might leak or pass. Although the scores or creases, 100, in the flattened out blank are not diametrically extended, yet when the edges of the blank are joined at the cut or incision, a radially extending crease or score at one side of the center alines with the opposite crease or score and the two constitute a diametrically extending crease or score. It will thus be seen that by two folds, first, on one diametrically extending score or crease, and then on the other diametrically extending score or crease, the flat triangular state of the article shown in Fig. 2 can be produced and thus that compact state important for storage and handling for sale, can be produced or secured.

Where the strip, 12, overlaps the adjacent triangular side, a suitable permanent connection is provided either by some suitable adhesive or by wire fasteners at intervals.

In order to simulate or resemble the usual umbrella appearance, the periphery of the blank and the finished article may be scalloped.

It is, of course, desirable to have the protector extending outward from the person when resting on the head, as much as possible, to give protection from the elements equal to that of the ordinary umbrella, and yet it is important that the vision or view of the wearer be obstructed as little as possible, and that the conditions of wearing the article in crowds of persons be taken into account so that undue space will not be required. The ordinary umbrella by reason of its circular form extends needlessly far in front of the user, and yet it is impractical to depart from the circular form of the ordinary umbrella. However, with my article, I am able to deal with conditions not feasible with the ordinary umbrella. I, therefore, prefer to make the article so that the base of the pyramid when the article is upon the head of the wearer, is shorter from front to back than from side to side, and I also make the front edge extend not so low as the rear edge. Thus the article has all required extent laterally to reach over the shoulders of the wearer and rearwardly to reach over the back of the wearer and forwardly without encroaching

on space required for one's neighbor and without dangerously obstructing the view or vision of the wearer, either forward or to either side.

Of course, no handle in the form of a stick as in an ordinary umbrella is provided, and none is necessary. The article rests upon the head or hat of the wearer. It is desirable, however, to provide convenient means for holding it in place. Such means may advantageously consist of ribbon or string or cord, 13, which preferably is a single piece that is attached at its ends equidistant from the center or apex in the sidewise direction of the article so that when the article is on the hat or head of the wearer the flexible holding member will hang in a loop, in front of the face of the wearer and at the bottom of the loop, the thumb or fingers can be placed comfortably to hold the article in place. I prefer the one-piece loop because it assures balanced pull on the article so as to maintain it in a proper, central position. The ends of the flexible loop are secured suitably to the underside of the sheet and in rear of the adjacent score or crease, so that no strain will be localized on the score or crease, and so that there will be no tendency to lower the front of the article.

By reason of its compact form when folded and the ease with which it may be opened out for use, it is feasible for a supply for sale to be supplied on buses which provide seats for passengers on the top or deck where they are exposed for protecting the passengers and for that matter for passengers wherever seated who are obliged to leave the bus in a down-pour of rain; they can be conveniently carried in automobiles for emergency use either in riding in open cars or in going to and from the cars, and one in leaving his home when weather conditions indicate rain, but who does not wish to be bothered with an umbrella, may easily and inconspicuously carry one,—for in the folded state it is no bulkier than an ordinary newspaper. They can be sold by the use of slot machines and in ten-cent stores. They can be used as attractive advertising devices so that containing advertisements they could be given away.

In use in rain, there is no tendency of rain-water to localize and run in streams, but there is distribution of the rain-fall, although without saturation, and this is an important factor in avoiding collapse or break-down under wetting.

To facilitate putting the shield on in the proper position, the word "Front" may be printed on the margin or edge at the front.

It will be observed that three of the four radial creases form hinges for folding only in one direction in opening out and collapsing the umbrella, and that the fourth crease which is at the back permits folding in both

directions, and as the connections between the cord or holding ribbon are on opposite sides of the last mentioned crease, the pull thereon when the umbrella is opened out and on the head, tends to produce and maintain the out-bending at that crease and hence, to sustain the same.

What I claim is:

1. A shield for wear above and supported upon the head of a person, comprising a body of sheet material of hollow pyramidal form, having an even number of triangular sides the adjacent triangular sides of the pyramid meeting and forming thereat an outwardly bulging corner that extends in a radial line from the apex of the pyramid to the base, the material being of sufficient stiffness to resist collapse in the area from side to side of each triangle, and said body being foldable along said corners to place one flat portion thereof flat against another, the portions between the corner folds remaining in a flat state throughout their area.

2. A shield for wear above and supported upon the head of a person comprising a body of sheet material that has a hollow taper form with an even number of flat sides, said material having sufficient stiffness to resist collapse in the area within the edges of the sides, and adjacent sides meeting in a straight outwardly bulging ridge which provides a straight hinge on which such sides may fold to lie substantially flat against one another, said sides when folded retaining their aforesaid flat form, and means by which the body may be held in an opened out position upon the head with the sides diverging downwardly and outwardly from the top thereof.

3. A shield for support over the head of a person comprising a hollow pyramidal body of sheet material having an even number of sides, adjacent sides meeting in a straight outwardly bulging ridge that constitutes a reinforcement that extends from the apex of the pyramidal body towards the base thereof from which edge such adjacent sides diverge and said edge providing a hinge upon which said adjacent sides may fold to lie substantially flat against one another, said sides when folded retaining the same shape they have when the body is in a hollow pyramidal form.

In testimony whereof I hereunto affix my signature:

EUGENE ANDERSON.
